(57) **CLAIM**

The ornamental design for a pastry bag choker device, as shown and described.

DESCRIPTION

FIG. 1 is an exploded top, front, left side perspective view of a pastry bag choker device showing my new design.

FIG. 2 is a left side view thereof;

FIG. 3 is a top plan view thereof;

FIG. 4 is a left side view thereof, the right side view being a mirror image;

FIG. 5 is a bottom plan view thereof;

FIG. 6 is a perspective view thereof; and,

FIG. 7 is a perspective view thereof mounted on a pastry bag.

The pastry bag shown in FIG. 7 is shown in broken lines for illustrative purposes only and forms no part of the claimed design.
